UNITED STATES PATENT OFFICE.

MILTON A. GOWING, OF PORTLAND, OREGON.

TOOL HOLDER.

Application filed January 30, 1924. Serial No. 689,516.

To all whom it may concern:

Be it known that I, MILTON A. GOWING, a citizen of the United States, residing at Portland, in the county of Multnomah and 5 State of Oregon, have invented certain new and useful Improvements in Tool Holders, of which the following is a specification.

This invention relates to improvements in supporters for egg-beaters, hand-drills, and 10 the like.

The object of my improvements is the provision of a simple and convenient holder for the upper end of a manually or power driven tool whereby stability may be given 15 to the tool to increase the efficiency of the tool in the exercise of its functions and to the greater ease and convenience of the operator.

A further object of the invention is to 20 provide a holder of the class described that may be folded when not in use and maintained in disuse within convenient position for instant service.

A still further object of the invention is 25 the provision of simple and practical devices for securing the egg-beater or other device in relatively rigid condition in its operative positions.

It is the province of my invention to im- 30 prove generally the class of devices to which it appertains and particularly to tool-holders of the type described.

The invention consists in the novel construction and adaptation of a supporter for 35 tools, and in the combination of parts and devices for carrying out the above named and other objects, to be more fully described in the following specification, illustrated in the accompanying drawings, and finally 40 pointed out in the appended claims.

In said drawings, Figure 1 is a view in side elevation of an embodiment of my invention in folded condition.

Fig. 2 is a view similar to Fig. 1 showing 45 the holder in operative position and sustaining an egg-beater.

Fig. 3 is a perspective view of my invention on an enlarged scale in its open condition to receive a tool.

Fig. 4 is a fragmentary view in side elevation, partly broken away at its middle portion.

Fig. 5 is a view in cross section on line 5-5 of Fig. 4.

Referring to said views, in which similar characters of reference indicate like parts in

the several views, the reference numeral 10 indicates a back-board of rectangular configuration having opposite flat-plane faces 11 and 12 on its upper and lower sides, respectively. Said back-board is secured at one end 13 to a wall 14 or other rigid support by a hinge 15 so that it may be swung either up or down according to the manner in which the hinge is disposed to lie closely in parallel planes with the wall when not in use, as shown in Fig. 1, or extended outwardly in a horizontal plane, as seen in Fig. 2.

A clamping strip 16 is rigidly secured at 70 one end, as by screws 17, to the lower side 12 of the board adjacent its end 13 and extends parallel with and for the approximate length of the board. At the outer end of the board the strip is unconfined and being 75 desirably formed of spring-like material, such as metal or wood of suitable variety it may be readily separated from the board at its outer end 19 to receive the handle of the tool, as will be explained. Said strip is of 80 relatively wide dimensions to fill the hand-opening of the handle 28 of the tool to be held thereby.

A gripping-bar 20 is rigidly secured at 85 right angles to the under side of said strip 16 and a complementary bar 21 is hingedly connected thereto at one end, as at 22. Said bars may be secured in spaced relation when in use by a U-shaped clip 23 pivoted 90 upon the opposite end of the bar 20.

Upon the under side of the back-board 10 and in line with the space provided between said bars a transversely disposed groove 25 is formed to receive the handle 28 of the tool.

An egg-beater of a well-known type is shown in the drawings to illustrate the invention and in describing the manner of its use such an appliance will be utilized as 100 typical.

With the holder secured to the wall in hinged condition in the manner described and at a suitable height above a table or bench, designated at 26, to maintain the egg-beater in vertical plane when in operative 105 position and at right angles to the board 10, the looped handle 28 of the beater is passed over the free end 19 of the clamping strip 16 and with the gripping-bar 21 thrown back, as illustrated in Fig. 3, it is slid along said strip until the upper edge of the beater handle 28 is lodged in the groove 25. The 110

gripping member 21 is then swung forwardly and the shank 30 of the beater is gripped between the bars 20 and 21 and thus secured by the U-shaped clip 23. The assembled device is thereupon swung forwardly and downwardly to dispose the lower end of the beater within a bowl or pan 31 upon the table whereupon the functions of the beater may be conveniently performed.

The left hand of the operator grasps the end 18 of the back-board and the end 19 of the strip and thus firmly presses the portion 28 of the beater-handle within the groove 25 to secure the upper end of the beater rigidly while the grip of the bars 20 and 21 upon opposite sides of the handle maintains the beater in rigid operative relation approximately right angles to the back-board. The beater may be used with ease and satisfactory results as it is secured in an efficient manner and cannot slip about the bowl at its lower end nor shift about at its upper end as is usually the case when the beater is held in the hands of the operator.

The beater may be quickly removed from the holder and the latter may then be swung against the wall to remain out of the way until needed for use again.

It is evident that my invention is adapted as a support for a considerable class of

tools in addition to egg-beaters, and particularly for drills for wood or metal, and any such adaptation and such modifications of design as may be made within the spirit of the invention and the scope of the claims are deemed as being within the bounds of my invention.

Having described my invention, what I claim is—

1. A tool-holder of the class described consisting in a back-member hingedly connected to a support, a strip connected at one end to said member and separable at its opposite end therefrom to receive a tool-handle therebetween, and a pair of separable gripping-bars for the shank of said tool, one of said bars being secured to said strip and the other bar being hingedly connected to the secured bar.

2. A tool-holder of the class described, consisting in a back-board hingedly connected to a support and having a tool-receiving groove in its lower side, a resilient strip secured at one end to said back-board and adapted to press the handle of a tool within said groove, and a pair of bars mounted on said strip for securing the shank of said tool against side deflection.

Signed at Portland, Oregon, this 15th day of January, 1924.

MILTON A. GOWING.
